UNITED STATES PATENT OFFICE.

LAWRENCE A. SUBERS, OF EAST CLEVELAND, OHIO.

AUTOMATICALLY-ACTING DEVICE FOR COATING THE YARN ELEMENTS FROM WHICH A LAMINATED COHESIVE INTERWOUND FABRIC BAND IS CONSTRUCTED.

1,223,636.

Specification of Letters Patent. Patented Apr. 24, 1917.

Original application filed February 19, 1912, Serial No. 678,696. Continuation of renewed application filed February 5, 1913, Serial No. 746,420. This application filed August 17, 1914. Serial No. 857,074.

To all whom it may concern:

Be it known that I, LAWRENCE A. SUBERS, a citizen of the United States, and resident of East Cleveland, in the county of 5 Cuyahoga and State of Ohio, have invented certain new and useful Improvements in Automatically-Acting Devices for Coating the Yarn Elements from which a Laminated Cohesive Interwound Fabric Band is Constructed, of which I hereby declare the following to be a full, clear, and exact description, such as will enable others skilled in the art to which it appertains to make and use the same.

15 This device is an improvement upon the coating mechanism shown and described in my former application Ser. No. 668,625, filed December 30, 1911, for coating the parallel yarn elements from which a laminated-cohesive-interwound fabric band is 20 constructed.

In the previous application a device for 25 constructing a fabric band was shown provided with a tapered mandrel of two diameters, upon the larger portion of which yarn elements were interwound and laminated and crossed each other at a predetermined angle, and the yarn elements were passed through a bath of coating material and exposed to vacuum and heat prior to winding 30 them upon the larger portion of the mandrel and were afterward pulled off from the smaller extremity thereof at a reduced relative angle to each other.

35 In the former device an arrangement of grooved, concentric coating cylinders were employed wherein each of the yarn elements composing the band was separately and completely coated and frictioned before being 40 interwound and laminated upon the mandrel.

In this improved device the yarn elements 45 are first properly interwound and laminated upon the larger portion of the mandrel under a predetermined tension and as the band is drawn along the mandrel it passes into a reservoir containing liquid rubber cement or other adhesive material, and is expanded therein, thereby diametrically 50 separating each yarn element circumferentially from the other, and completely coating and saturating them. After emerging therefrom the band passes over the reduced

extremity of the mandrel, contracting in diameter, by reason of the tension, till the 55 yarn elements are in their smallest angular position in the fabric, and so when the band passes off the tapered extremity of the mandrel all the yarn elements in the band will be closely drawn together and will be uniformly coated throughout. Winding the 60 yarn elements upon the portion of the mandrel of greater diameter at a larger angle than desired in the finished band and then decreasing the angle by drawing the band 65 under tension from the smaller extremity of the mandrel, greatly facilitates the construction of a band from yarn elements extending longitudinally at a smaller angle than they can readily be wound.

70 Another means of expanding the series of yarn elements for coating purposes consists of winding the four constituent series of yarn elements respectively about a forming tube and three non-rotating, encompassing, 75 concentric cylinders attached to the framework of the machine. The four series of a predetermined number of yarn elements are conducted to the mandrel and cylinders in the same manner as in the other method 80 but are drawn over the mandrel and cylinders out of contact with each other to a predetermined point when they pass from the cylinders to the forming tube, forming a perfect interwound laminated band. The 85 liquid rubber cement or other adhesive material is applied by an encompassing rubber cup just before the contact of the various series of yarn elements with the forming tube and they then pass to the vacuum and 90 heat chamber, or, after a predetermined amount of the various series of yarn elements have been interwound and laminated upon the mandrel, the previous method 95 herein described of expanding and treating the yarn elements on the mandrel may be utilized.

Thus by this other means the fabric band 100 is also interwound, laminated and coated before being exposed to the vacuum and heat. A long series of experiments seem to show conclusively that in constructing fabric bands of this character in which the angle of interwinding may vary from approximately 4° to 45° , the employment of 105 both these methods in the same machine are

necessitated as the first mentioned means employed for interwinding the yarn elements at a 4° angle is not so advantageous as the second means for interwinding a 5 fabric band of a 45° angle, since the resistance to pulling the band along the mandrel when interwound at this latter angle is much less when the series of yarn elements are divided among the mandrel and the 10 three encompassing cylinders.

The mechanism by means of which these results are obtained is hereinafter described, illustrated in the accompanying drawings and specifically pointed out in the claims.

15 In the accompanying drawings Figure 1 is a longitudinal section of the receptacle for coating and saturating the yarn elements and of the vacuum chamber in which the coating on the fabric band is solidified 20 by the evaporation of the solvents therein. In this view the expanding device within the rubber receptacle is shown, and the sliding gates by means of which the escape of rubber through the opening through which 25 the fabric passes can be prevented, when the machine stops. Fig. 2 is an enlarged elevation of a portion of the mandrel showing the cylindrical portion of larger diameter on which the yarn elements are first 30 wound, the expanding device, and the outer portion of the mandrel of smaller diameter, from which the laminated fabric is removed; Fig. 3 is a transverse section of the mandrel on line $l-l$ Fig. 1, showing 35 the expanding device; Fig. 4 is a longitudinal central section of the mandrel and expander; Fig. 5 is a front elevation of the receptacle for rubber, reduced in size, showing the overlapping flexible retaining plates 40 for the rubber; Fig. 6 is a transverse section through the rear wall of the receptacle on line $g-g$ Fig. 1, showing the sliding gates and guide slots and pins therefor; Fig. 7 is a transverse section of the front 45 wall of the receptacle on line $f-f$ Fig. 5, showing the overlapping retaining devices for the rubber; Fig. 8 is a perspective view of one of the sliding gates; Fig. 9 is a detail of one of the guiding rods for the yarn 50 elements showing guiding and tension applying devices; Fig. 10 is a plan view of the vacuum drying chamber, and includes plan views of the rubber tank, vacuum pump and air compressor, by means of 55 which the coating material, preferably rubber, is put under pressure in the rubber tank, and is forced into the reservoir in the band forming machine; Fig. 11 is a vertical section of the rubber tank; Fig. 12 60 is a vertical longitudinal section of the reels showing the expanding cylinders for the bands and supports therefor; Fig. 13 is a front view of four of these brackets; Fig. 14 is a longitudinal section of portions of 65 these guide cylinders.

In these views B^5 is a cylindrical mandrel upon which the bands of yarn elements are laminated to form the fabric band. This mandrel is provided with a tapered portion B^6 and a smaller cylindrical portion X terminating in a flattened extremity X' which is adapted to flatten the fabric band prior to entering the vacuum chamber G .

Z is a chamber for fluid rubber, divided in halves secured together for access to the 75 interior for cleaning, and is provided with a base portion Z' by means of which it is bolted to the end of the vacuum chamber G . The mandrel extends through openings Z^2 and Z^{15} in this chamber.

The opening Z^2 in the outer end is closed by means of overlapping washers Z^3 of leather or other flexible material held in place by a metal washer Z^4 which is divided in half to correspond with the divisions of the chamber and is secured thereto by means of screws Z^5 , and the opening Z^{15} in the inner end is closed by the walls Z^6 of the chamber which contains sliding gates Z^7 , Z^8 which can be opened or closed by rotating the plate Z^8 . This plate is provided with the bevel gear Z^9 engaging the gear Z^{10} upon a shaft Z^{11} , so as to automatically close the opening Z^{15} in the wall of the chamber Z when the machine stops and prevent the escape of rubber or other adhesive substance therefrom.

The gates Z^7 are operated by pins Z^{12} fixed thereon, and by means of cam shaped openings Z^{13} in the rotatable plate or disk Z^8 . By this means the gates are made to slide radially in the inner end wall Z^6 of the chamber Z in grooves Z^{16} , Z^{17} .

The forming tube or mandrel B^5 is provided with an annular recess L^4 registering with the gates Z^7 so that when a knot or other obstruction passes the edges of the opening Z^{15} in the wall Z^6 of the chamber Z , the band is depressed into the annular recess L^4 .

C^4 , C^4 are guide rods and C^{10} , C^{10} are guide rollers by means of which the several yarn elements F , F , are applied to the mandrel, and the rods and guide rollers rotate about the mandrel so as to wind the yarn elements F thereabout at the required angles. The yarn elements are placed under tension by means of guide and tension rollers C^2 , C^2 and R^{20} , R^{20} mounted upon the stands R^{19} , R^{19} which are in turn secured upon the reels B , B' , B^2 and B^3 , one of which B^2 is indicated in Fig. 9. Substantially in the center of the rubber receptacle is shown the expanding device 115 preferably comprising a ring Z^{24} having an annular edge Z^{25} of greater diameter than the mandrel. Over the edge of this ring the constituent yarn elements of the fabric band are pulled under suitable tension so as to momentarily expand and separate 120

them in order that the coating material will flow between them, and coat and saturate every portion thereof.

At a predetermined distance from the expanding ring Z^{24} in the chamber Z are angular surfaces terminating in apices Z^{26}, Z^{26} concentric with the mandrel, whose functions are to confine the yarn elements as they approach and recede from the expanding ring and also to partially control the tension of these yarn elements in passing over this ring.

The expanding ring Z^{24} also serves to provide a space between the mandrel and the yarn elements so that the rubber coating material will also have access to the inner surface of these yarn elements. The exterior surfaces are also coated as the yarn elements pass through the receptacle, and the thickness of the outer coating is determined by the diameter of the opening Z^{15} in the inner wall. The fabric band is pulled from the mandrel by means of rollers H^2 grooved at H^9 to permit the evaporation of the solvents from all portions of the band and the solidification of the coating thereon. One of these rollers is seen in Fig. 1 in the vacuum chamber G .

The mandrel is provided with longitudinal grooves D^6, D^6 which pass underneath the expanding ring Z^{24} so as to give free circulation to the coating material and access therefor to the inner sides of the yarn elements.

The mandrel shown in Fig. 4 is hollow and is provided with radial openings D^7, D^7 which communicate with the grooves D^6 and if desired the rubber coating can be fed through these openings to the yarn elements and rubber receptacle.

A valve D' having radial openings D^2 can be employed to control the passage of the rubber or other adhesive material through the openings D^7, D^7 . An eccentric opening D^8 extends through the outer flattened extremity of the mandrel and is controlled by means of the valve D' having an eccentric opening D^9 , so that rubber can be introduced into the interior of the fabric if desired. Ordinarily however rubber can be fed to the receptacle Z through a pipe E^{16} . Pressure is applied to the rubber in the tank E^{30} so that the rubber will be supplied to and completely fill the receptacle Z and thus no portion of the fabric can escape treatment.

In Figs. 10 and 11 are shown the vacuum chamber G , the suction or vacuum pump H^{20} and connecting pipe H' . The rubber tank E^{30} is provided with the piston E^{31} , gage E^{32} , air pressure pump E^{33} , and connecting pipe I' and E^{16} . In Fig. 9 is shown a portion of one of the rotating reels B^2 which wind the yarn elements about the mandrel, a split standard R^{19} attached thereto, spring

pressed rollers C^2 and R^{20} mounted on the standard R^{19} which likewise supports the guiding rod C^4 on which is mounted the guiding rolls C^{10} and C^3 for the yarn elements F . The spring pressed rolls C^2 and R^{20} provide a predetermined tension for these yarn elements by means of the spring R^{22} . A complete description of the mechanism for interwinding and laminating these yarn elements about the mandrel is described in my former application Ser. No. 668,625, filed December 30, 1911.

In operation the yarn elements F, F are interwound under tension upon the larger portion of the mandrel B^5 at an angle wider than that intended to be permanent and hence open spaces are left between the crossing points. They then pass through the protected front wall of the receptacle Z containing liquid rubber cement or other adhesive material and thence pass over the expanding ring whose greater diameter not only separates circumferentially the yarn elements as units but also the yarns composing these elements and the several yarn elements are thus completely coated and saturated with the desired coating material.

On emerging from the receptacle Z the band is exposed to the heat and vacuum of the chamber G and passes over the tapered portion of the mandrel to that of less diameter where the bands assume under the tension a smaller relative angle and are brought closely together and the tubular fabric is flattened by the laterally expanded terminal of the mandrel, as it passes to the drying and pulling rolls H^2 .

The yarn elements in passing over the expanding ring Z^{24} are widely separated and in passing to the smaller part of the mandrel the elements readily slide over each other before the coating is solidified, the angle of winding constantly diminishing, and thus all of the points of crossing of the yarn elements in the finished band are completely coated.

In Figs. 12, 13, and 14 are illustrated a series of non-rotating expanding means, located exterior to the coating chamber, which serve to separate the yarn elements entirely out of contact with each other so that they will not overlap, before they are interwound and laminated upon the mandrel. This construction prevents any possibility of displacement of one or more of the bands from friction as they pass along the mandrel.

They are also widely separated both integrally and as units as they enter the coating material and are completely coated and saturated on all sides prior to and at the moment of coming together upon the small portion of the mandrel.

In these views 1, 2 and 3 are cylinders concentrically arranged about the larger end of the mandrel B^5 and are supported upon

arms 4, 4, 4 secured to the several reel supporting brackets B¹⁴.

The yarn elements from reel B' pass over the inside cylinder 1, whose extremity is set 5 slightly in the rear of the shoulder 5 on the mandrel; the yarn elements from reel B² pass over the intermediate cylinder 2 whose extremity is set slightly back from that of cylinder 1, and the yarn elements from reel 10 B³ pass over the outside cylinder 3 whose extremity is set slightly back from that of cylinder 2, thus giving to all the yarn elements a corresponding angle of inclination to the mandrel, serving to concentrate them 15 on a small portion of the mandrel and also serving to elevate them above the smaller portion X of the mandrel, so that the coating 20 material will have equal access to all.

In Fig. 12 the receptacle G' is attached to the vacuum chamber G, having a nozzle G² through which the mandrel and yarn elements thereon have access to the chamber. The mandrel and yarn elements F enter the receptacle G' through the aperture G³ which 25 closely surrounds the elements which by their forward movement along the mandrel tend to prevent the rather viscous rubber cement or other adhesive material from escaping. The rubber cement is supplied 30 through the pipe E¹⁶.

The location of the expanding means may be also at any desired point on the mandrel.

It is obvious that the constituent elements of this fabric band may be of any desired 35 form of material other than that herein specifically described, without departing from the spirit of the invention or the scope of the claims.

It is also obvious that by the use of any 40 suitable adhesive substance for the purpose of coating the elements composing the fabric band that the same may be applied at any predetermined high temperature and the band then be exposed to a predetermined 45 low temperature for solidifying the same without departing from the spirit of the invention or the scope of the claims.

It is evident that any predetermined number 50 of expanding rings or cylinders and accompanying confining means may be used and located at desired points on the forming tube or mandrel for the purpose indicated, without departing from the spirit of the invention or the scope of the claims.

By the term "yarn element" as used in 55 these specifications and claims is meant a group of close lying parallel yarns or threads of a predetermined number and diameter forming a flat band.

Having described the invention, what I 60 claim as new and desire to secure by Letters Patent is:

1. In a device for forming a laminated-cohesive-interwound tubular fabric from 65 yarn elements, and for coating the same, a

mandrel upon which the yarn elements are wound and cross each other at an angle, a receptacle for coating material through which the mandrel passes, and an expanding device concentric with said mandrel over 70 which said yarn elements pass, and means for pulling said yarn elements over said mandrel and expanding device, and a tension device for each yarn element.

2. In a device for the purpose described, 75 a mandrel upon which bands of flexible material are interwound, a chamber for coating material through which said mandrel passes, and expanding means concentric with said mandrel over 80 which said bands pass to expose the same separately to the said coating material in said chamber.

3. In a device for constructing a laminated-cohesive-interwound tubular fabric, 85 and for coating the yarn elements composing the same, a mandrel, a chamber for coating material through which the mandrel passes, stationary annular expanding means concentric with the mandrel over 90 which said yarn elements are drawn, and means for placing said yarn elements under tension.

4. In a device for constructing a laminated-cohesive-interwound fabric, said fabric composed of yarn elements, a mandrel, means for rotating the yarn elements about 95 said mandrel, means for pulling the yarn elements over the mandrel and for supplying tension thereto, a chamber for coating material through which the mandrel and fabric extend, and means for temporarily separating the yarn elements and constituent yarns while passing through said chamber to expose the yarn elements and constituent yarns separately to contact with the coating material therein. 105

5. In combination, a mandrel upon which a laminated-cohesive-interwound fabric composed of yarn elements is constructed, a chamber for fluid coating material through which said mandrel passes, an annular expanding device upon said mandrel within said chamber, said mandrel being provided with grooves in its outer surface passing underneath said annular expanding member and on both sides thereof, said mandrel being provided with passages communicating with said grooves, a valve controlling the said passages, and means for introducing fluid coating material under pressure to said chamber and to said valve. 110

6. In a device for the purpose set forth, a chamber for fluid coating material, a mandrel passing into said chamber and having a cylindrical body portion and a flattened extremity, expanding means upon said mandrel encircling the cylindrical portion thereof and located within said chamber, said mandrel being provided with a central passage, and with longitudinal grooves extending on both sides of said expanding means, 125 130

and with radial openings connecting said central passage and said grooves, and a valve controlling said radial openings.

7. The combination with a mandrel upon which a laminated-cohesive-interwound fabric is constructed from yarn elements, a chamber for fluid coating material through which said mandrel passes, an annular expanding member in said chamber and upon said mandrel over which said fabric passes, said mandrel provided with an opening to admit coating material underneath said expanded fabric, and a valve in said opening.

8. In combination, a mandrel upon which a laminated-cohesive-interwound fabric composed of yarn elements is constructed, said mandrel provided with a portion of large diameter, a portion of smaller diameter, a chamber for fluid coating material through which said mandrel passes, an annular expanding device upon said mandrel within said chamber, said mandrel provided with grooves passing between said annular expanding device and said mandrel, and said mandrel provided with passages communicating with said grooves, a valve controlling the said passages, and means for introducing fluid coating material under pressure to said chamber and to said valve.

9. In a device for constructing a laminated-cohesive-interwound fabric upon a mandrel and for coating the same, in combination with said mandrel, said mandrel having portions of large and small diameter, a ring having a narrow edge and sleeved over the larger portion of said mandrel, guiding and tension devices operating to interwind and laminate said fabric on the larger portion of said mandrel, means for pulling the fabric over said mandrel, and over said ring to temporarily expand the same, and finally over the smaller extremity of said mandrel, and means for supplying coating material to the fabric while expanded upon said ring.

10. In a device for constructing a laminated-cohesive-interwound fabric upon a mandrel, in combination a mandrel, said mandrel provided with a tapered extremity and with an opening passing therethrough and with radial openings, all said openings

communicating with a central opening, and a common valve controlling all said openings.

11. In a device for the purpose set forth, a mandrel having portions of two diameters, a chamber for fluid coating material, an expanding means upon said mandrel located within said chamber, said mandrel provided with a central passage, and with longitudinal grooves extending on both sides of said ring, and with radial openings connecting said central passage and said grooves and valve controlling said radial openings.

12. In a device for coating flexible bands, interwound upon a mandrel to form a laminated cohering fabric, the combination with the mandrel, of a chamber for coating material, and means for temporarily expanding the said fabric to separate said bands when passing through said chamber, whereby each band will be separately exposed to said coating material.

13. In a device of the class described, a chamber for fluid coating material, a mandrel passing into said chamber and having a cylindrical body portion and a flattened extremity, expanding means upon said mandrel encircling the cylindrical portion thereof and located within said chamber, said mandrel being provided with a central passage, and with longitudinal grooves extending on both sides of said expanding means, and with radial openings connecting said central passage and said grooves.

14. In a device of the class described, a chamber for fluid coating material, a mandrel passing into said chamber, and expanding means upon said mandrel encircling the portion thereof within said chamber, said mandrel being provided with an internal passage and with longitudinal grooves extending on both sides of said expanding means, and with openings connecting said central passage and said grooves.

In testimony whereof, I hereunto set my hand this fourteenth day of August 1914.

LAWRENCE A. SUBERS.

In presence of—
ERNEST MOSMAN,
A. T. OSBORN.
